(57) **CLAIM**

The ornamental design for a skin treatment device, as shown and described.

DESCRIPTION

FIG. 1 is a front view of a skin treatment device showing our new design;

FIG. 2 is a rear view thereof;

FIG. 3 is a left side view thereof;

FIG. 4 is a right side view thereof;

FIG. 5 is a bottom end view thereof; and,

FIG. 6 is a top end view thereof.

The broken line showing of parts of the drawings is included for the purpose of illustrating use and environment and forms no part of the claimed design.
